UNITED STATES PATENT OFFICE

GEOERGE A. STACKHOUSE, OF OAKLAND, CALIFORNIA, ASSIGNOR TO L. A. YOUNG SPRING AND WIRE CORPORATION, OF DETROIT, MICHIGAN

SPRING STRUCTURE

Application filed February 26, 1930. Serial No. 431,400.

The main objects of this invention are:

First, to provide a spring structure which is well adapted for use as a mattress or cushion filler.

Second, to provide a spring structure of this character which presents a substantially smooth surface, that is, there are no projections likely to injure or wear the upholstery portion of the mattress.

Third, to provide a spring structure of the class described in which the body springs are effectively supported in upright spaced relation and at the same time are yieldably connected for free movement and so that movement of the springs is not likely to cause noise.

Fourth, to provide a structure having these advantages which is economical to produce and one which permits certain assembling operations by machinery.

Objects relating to details and economies of my invention will appear from the description to follow. The invention is defined and pointed out in the claims.

A structure which is a preferred embodiment of my invention is illustrated in the accompanying drawings, in which:

Fig. 1 is a fragmentary plan view of a spring structure embodying the features of my invention, parts being arranged to show the method of assembling.

Fig. 2 is an enlarged detail view on line 2-2 of Fig. 1.

Fig. 3 is a fragmentary view illustrating one method of assembling.

Fig. 4 is a fragmentary view illustrating another method of assembling.

In the accompanying drawings I have illustrated only fragmentary portions of a mattress filler spring structure.

My improved spring structure comprises helically coiled body springs 1 arranged in rows, corresponding springs of the rows being also arranged in alignment. The end or terminal coils 2 of these body springs termi-

nate in laterally disposed terminals 3 while opposite these terminals the top coils have offsets 4 of substantial length, these offsets being straight as illustrated. With the springs of the several rows arranged in alignment these offsets are brought into alignment.

The terminals 3 of one of the springs of a row are loosely coiled about the offsets of an adjacent spring of the row, the coils 5 being spiral and open as shown in the drawings. This provides a loose pivotal connection for the several springs of the row.

The helically coiled spring cross members 6 are rotated to engage coils thereof with the offsets, with coils of the cross members lying between the coils 5 of the tie members and between these coils 5 and the ends of the offsets, so that the tie members are supported laterally on the offsets by coils of the cross members and the coils of the cross members do not interfere with the pivotal movement of the springs of the rows relative to each other, and the aligned springs in the rows are yieldably connected by these spring cross members.

The tie members 3 may be coiled about the offsets either before or after the cross members are engaged with the offsets.

In Fig. 3 I illustrate the method of assembling in which the cross members are engaged with the offsets prior to the engagement of the tie members therewith.

In Fig. 4 I illustrate the method of assembling in which the tie members are engaged with the offsets prior to the engagement of the cross members therewith, the open coils of the tie members permitting the cross members being engaged or threaded upon the offsets by rotation of the cross members.

With the parts thus connected, there are no substantial projections incident to the connections formed by the springs which would be likely to wear the upholstery.

My improved spring structure may be very

economically produced and is highly desirable as a filler for mattresses as the springs are permanently connected and so as to secure the advantages of the full resilience thereof.

5 Having thus described my invention, what I claim as new and desire to secure by Letters Patent, is:

1. In a spring structure, the combination of spirally coiled body springs disposed in

10 rows and having end coils terminating in laterally disposed tie members and having substantially straight offsets of substantial length opposite said tie members, the tie member of one spring being loosely coiled about

15 the offset of an adjacent spring, the coils of the tie member being open, the corresponding springs of adjacent rows being disposed with their offsets in alignment, and helically coiled spring cross members having open coils en-

20 circling the aligned offsets with coils thereof lying between the coils of the said tie members and other coils between the said tie mem-

bers and the ends of the offsets.

2. In a spring structure, the combination of spirally coiled body springs disposed in rows and having end coils terminating in laterally disposed tie members and having offsets opposite said tie members, the tie mem-

30 ber of one spring being spirally coiled about the offset of an adjacent spring, the corresponding springs of adjacent rows being disposed with their offsets in alignment, and helically coiled spring cross members encir-

35 clining the aligned offsets and having coils thereof lying between the coils of the said tie members.

3. In a spring structure, the combination of spirally coiled body springs disposed in rows and having offsets in their end coils, the ter-

40 minals of the end coils having helical coils en- circling the offsets of adjacent springs constituting tie members, the corresponding springs of adjacent rows being disposed with their offsets in alignment, and helically coiled

45 spring cross members having open coils en- circling the aligned offsets and with coils thereof lying between the helical coils of the tie members and other coils embracing the off- set between the tie members and the ends of

50 the offset.

4. In a spring structure, the combination of spirally coiled body springs disposed in rows and having offsets in their end coils, the ter-

55 minals of the end coils having helical coils en- circling the offsets of adjacent springs constituting tie members, the corresponding springs of adjacent rows being disposed with their offsets in alignment, and helically coiled

60 spring cross members having open coils en- circling the aligned offsets and with coils thereof lying between the helical coils of the tie members.

5. In a spring structure, the combination of spirally coiled body springs disposed in rows

65 and having end coils with offsets therein, the

ends of the end coils having helical coils en- circling the offsets of an adjacent spring pro- viding ties therefor, the corresponding springs of adjacent rows being disposed with their offsets in alignment, and helically coiled

70

spring cross members having open coils en- circling the aligned offsets with coils thereof disposed between the helical coils of the

spring tie members.

In witness whereof, I have hereunto set 75

my hand.

GEORGE A. STACKHOUSE.
